Design No. 11,677, dated March 9, 1880.

UNITED STATES PATENT OFFICE.

WILLIAM BAYLEY, OF MILWAUKEE, WISCONSIN.

DESIGN FOR VASE AND PEDESTAL.

SPECIFICATION forming part of Design No. 11,677, dated March 9, 1880.

Application filed February 19, 1880. Term of patent 7 years.

To all whom it may concern:

Be it known that I, WILLIAM BAYLEY, of Milwaukee, in the county of Milwaukee and State of Wisconsin, have invented and produced a new and original Design for Vase and Pedestal, of which the following is a specification, reference being had to the accompanying drawing forming part thereof.

My design for vase and pedestal will be clearly described and distinctly pointed out in the following specification and claims.

The drawing represents an elevation of my newly-designed vase and pedestal, which consists in a bowl, A, having egg-moldings *a* about its rim, ornamental handles *C c c'*, tapered body ornamented by arched flutes *E*, and blending with ornamented bulge *F*, to be reduced at *g* and terminated in another bulge, *H*, and a stand, *I*, ornamented at *i j*.

My improved ornamental pedestal has the ordinary top, but about and around its capital has a groove, *K*, having its lower edge serrated, as at *K'*.

The body *L* of the pedestal is square, and is

assisted in supporting the top by ornamental pillars *M*, having central ornaments, *m*, the whole resting on ornamented base *N*.

I claim—

1. The design for vase herein shown and described, the same consisting of the bowl A, having egg-molding *a* about its rim and ornamental handles *C c c'*.
2. The design for vase herein shown and described, consisting of the bowl A, having bulge *F*, and both ornamented, as shown.
3. The stand I, ornamented as shown at *i j*, as a new and ornamental design.
4. The pedestal having ornaments *K K' N* and pillars having ornaments *m*, as a new and ornamental design.

In testimony that I claim the foregoing as my own design I hereto set my hand, in presence of two witnesses, this 29th day of December, A. D. 1879.

WILLIAM BAYLEY.

In presence of—

E. H. BOTUM,
ALEX. GREENSLADE.
